(57) CLAIM

The ornamental design for an adhesive stencil, as shown and described.

DESCRIPTION

FIG. 1 is a perspective view showing my new design;

FIG. 2 is a front elevational view;

FIG. 3 is a rear elevational view;

FIG. 4 is another perspective view showing my new design
in use.

FIG. 5 is a bottom view of the first embodiment of the adhesive stencil engaged with the associated liner;

FIG. 6 is a rear view of the first embodiment of the adhesive stencil engaged with the associated liner; and,

FIG. 7 is a perspective view of the first embodiment of the adhesive stencil being disengaged from the associated liner
by an associated user.

The broken lines in the drawings depicting portions of the adhesive stencil are for illustrative purposes only and form no part of the claimed design.
